UNITED STATES PATENT OFFICE.

DWIGHT T. CLARK, OF EAST ORANGE, NEW JERSEY.

COIN-CONTROLLED VENDING MACHINE.

Application filed January 19, 1928. Serial No. 247,912.

This invention relates to vending machines, and particularly to an improved coin controlled vending machine, wherein the parts have been simplified while retaining a number of safety or projecting appliances which prevent the use of most spurious coins without interfering with the proper operation of the machine when a genuine coin is used.

10 The object of the invention is to provide a simplified form of coin controlled vending machine, wherein the parts are so constructed that there is little liability of getting out of order, while at the same 15 time functioning properly, notwithstanding abuse through the attempted use of washers or other spurious coins.

Another object of the invention is to provide a coin controlled vending machine 20 which is easy to operate, and which will automatically lock itself against operation when the last article has been vended.

A still further object of the invention is to provide in a coin controlled vending machine, means for permitting the actuation 25 of the machine once after a coin has been inserted, with the parts so arranged as to prevent a second operation.

In the accompanying drawings—

30 Figure 1 is a longitudinal vertical sectional view through a vending machine, disclosing an embodiment of the invention, the operating mechanism being shown in elevation.

35 Figure 2 is a longitudinal vertical sectional view through the lower part of the vending machine shown in Figure 1, said view being taken approximately on line 2—2 of Figure 6.

40 Figure 3 is a fragmentary sectional view through Figure 2, approximately on line 3—3.

Figure 4 is a view similar to Figure 2, but showing the parts moved slightly toward an operated position.

45 Figure 5 is a fragmentary sectional view through Figure 2, approximately on line 5—5.

Figure 6 is a horizontal sectional view 50 through Figure 1, approximately on line 6—6, the same being on an enlarged scale.

Figure 7 is a fragmentary sectional view through Figure 2, approximately on line 7—7.

55 Referring to the accompanying drawings by numerals, 1 indicates a support of any

kind, as for instance, a post or wall. A screw 2, having a large head, is carried by the wall 1 and is adapted to fit into the slot 3 in the back wall 4. This back wall telescopically fits into the casing 5 and the casing is held thereto by reason of the forwardly extending portion 6 having a depending flange 7 engaged by the bolt 8 of the lock 9. At the lower end, the wall 4 is provided with a forwardly extending section 10 carrying one or more lugs 11 which are adapted to be thrust through desirable openings 12 in the bottom 13 of casing 5. When it is desired to move the casing 5 to 70 secure across to the interior of the casing, lock 9 is unlocked by a suitable key and casing 5 grasped at the upper part and swung outwardly until free of member 6. The casing is then lowered until free of the lug 75 or lugs 11. The wall 4 is provided with a forwardly extending flange 14 on each side which slidingly fits into the casing 5 and thereby prevents any one forcing an instrument into the casing at this point. In 80 addition, a curved bracing member 15 is soldered or otherwise secured to members 4 and 10 at the lower end. This bracing member acts as a chute for guiding articles vended from the magazine 16 to the bottom 85 13 near the opening 17. The opening 17 is sufficiently large to permit part of a hand to be inserted so that the chewing gum or other articles vended may be readily grasped and removed.

The casing 5 is provided with a transverse bar 18 near the top, and this bar carries one or more retaining and guiding loops 19 through which the magazine or magazines 16 are loosely forced. As indicated 90 in Figure 6, the casing 5 is sufficiently large for three magazines 16 and three duplicate actuating mechanism, but only one has been shown completely, but as the others are identical, the description of this one will apply to the others. It is, of course, evident that in a vending machine only one mechanism may be used, or a large number, as each separate mechanism and associated parts, are identical with the other mechanisms and associated parts. The magazine 16 is preferably rectangular because the goods are of that shape, and preferably closed except at the front as indicated in Figure 6. One or a large number of articles 110 20 may be placed in the magazine 16 and then a follower block 21 placed on top.

This follower block may be of any desired material, as for instance, cast iron or brass, whereby ample weight is provided for holding the articles in proper position to be ejected. Preferably the follower block 21 is provided with a pair of depending legs 22, there being one leg on each side whereby the weight is placed on the articles 20 near the respective ends. Pivots mounted on top of the follower block 21 is a locking plate 23, which plate is rounded at 24 and provided with an aperture 25 adapted to receive a pin 26 as the last article 20 is ejected. This will prevent the pin 26 and associated parts, including the plunger 27, from moving back to the position shown in Figure 2.

As the plunger is locked in an inner or operated position, customers will know that the particular magazine associated with this plunger is empty. If for any reason, a person should drop a coin into the coin slot 28, it will merely drop down in front of the wall 29 and land on the bottom 13 where it may be readily recovered by inserting the hand through opening 17. At the lower end, the magazine 16 is provided with a notch 30 on each side, said notches accommodating the upstanding portions 31 of the wall 32. In this way the magazine is removably placed in position so that whenever the casing 5 is removed, the magazine may be quickly removed so as to supply the same with additional articles 20.

When a coin is dropped through the coin slot 28, it will pass downwardly through the opening 33 and also through the opening 34 into the space or chamber 35. If the coin is of magnetic material, as for instance, an ordinary iron washer, the magnet 36 will attract the same and hold the coin opposite the magnet so that when the plunger 27 is pushed, the coin will drop down in front of the wall 29 and strike the bottom 13 without causing an ejection of one of the articles 20. If the coin is not magnetic but has a hole in the center, it will pass the magnet 36 and strike the shoulder 37 of what may be termed a weighing mechanism 38.

If the coin is of the usual weight it will swing this weighing mechanism to one side and the coin will drop down until it strikes the wall 39 and pin 40. As indicated in dotted lines in Figure 3, when the plunger 27 is actuated, it will merely push the coin onto the actuating pin 41 as the coin has a hole therein. If the coin was not magnetic, but not as heavy as a genuine coin, it would rest on the shoulder 37, and

when the plunger 27 is actuated, it would drop past the end of the actuating pin 41 and, therefore, fail to operate the mechanism. If the coin was, however, of the right kind, as for instance, a genuine one cent piece, it would pass the magnet 36, strike

shoulder 37 and swing the weighing mechanism out of the way and move down until it rested on the pin 40 and against the wall 39. When the genuine coin is in this position and plunger 27 is forced inwardly, the actuating wall 42 will push the coin against the end of the actuating pin 41 and move the pin and associated mechanism forwardly as indicated in Figure 4. After the first slight movement, the enlarged end 75 or section 41' of pin 41 will move the rack 43 sufficiently to receive the end of pawl 44 into the first notch. If the pressure on the plunger 27 was released, the parts would not move back, though the plunger 27 would move back. However, by the time that the end of pawl 44 engaged the first notch in rack 43, the coin would be occupying a space over but at the left of wall 29, whereby when the wall 42 and associated parts move back the coin will be dropped into the coin container or receptacle 45. This, of course, will not eject any of the articles 20, but by again pushing the plunger 27, the parts will be further actuated, and if the plunger 90 is pushed in as far as possible, the ejector 46 will force the lowermost article 20 onto the chute 15 as indicated somewhat in Figure 4 and this article will slide down to a point near opening 17. After this actuation, the plunger 27 is released, and the parts again moved back to the position shown in Figure 2 ready for a second actuation. If the plunger 27 was actuated a second time without a coin, it would merely move inwardly without causing an actuation of any of the parts. This is caused by the fact that the wall 42 is really a U-shaped structure and rigidly secured to the respective walls 39, so that when moved forwardly 100 without a coin resting on the pin 40, no movement will be given to the pin 41. The pin 41 is guided by reason of the fact that it extends through a suitable aperture in an upstanding wall 47 carried by the base 110 plate 48, which base plate merges into the wall 32. A web or upstanding flange 49 is formed integral with or rigidly secured to the auxiliary pin or section 41', and to this web is rigidly secured or formed integral therewith, the ejector 46. This ejector consists preferably of a flat plate 50 having an upstanding flange 51 on each side. The pin 26 is rigidly secured to the plate 50 and extends upwardly through the U-shaped magnet 36 so that when spring 52 acts to force the plunger 27 and walls 39 back to their former position as shown in Figure 2, the magnet which is secured to these walls will pull pin 26, ejector 46 and associated parts back to their starting point. The walls 36 and 42 and associated parts, may be called an actuating frame as the same are moved by the plunger 27 and cause both a forward and rearward movement of the 115 120 125 130

other parts. One of the walls 39 is provided with a lateral extension 53 through which plunger 27 extends and to which the plunger is secured by any suitable means, 5 as for instance, a set screw. The plunger also slidingly fits into a suitable aperture in the wall 32 and through the front stationary wall 54 as well as through the front of the casing 5. Walls 32 and 54 are connected by a side plate 55, and in fact, the side plate 55, wall 54, wall 32 and base plate 48, may be of one solid casting or may be made separate and rigidly secured together. The base plate 48 and wall 32 10 are slotted for accommodating the rack 43, auxiliary pin 41' and web 49.

In respect to the action of the rack 47, it will be noted that the auxiliary pin 41' is provided with a single-notch 56 which is engaged by the bar 57, which bar has a pair of supporting arms 58 pivotally mounted at 59 on the walls 39 of the actuating frame. Ordinarily, the bar 57 is held out of notch 56 by a cam 57', but after notch 56 has been 25 moved through the insertion of a coin of the proper size, the bar 57 will drop down into this notch as shown in Figure 4 so as to force the auxiliary pin 41 and associated parts, including ejector 46, to a fully operated position before these parts will move 30 back to their starting point.

In case a washer having an aperture therein, has been pushed onto pin 41, said washer will remain on pin 41 until the pin 35 41 has been actuated by a correct coin. As soon as the pin 41 has been pushed inwardly by a correct coin as far as it will go, the coin will press the washer against ring 59 so as to slightly compress the spring 60. As 40 soon as plunger 27 is released, the spring 60 will function to force the washer off of the pin 41, whereby it will drop into the coin box along with the genuine coin.

In regard to the weighing mechanism 38, 45 it will be noted that the same is made up of plates 61 and 62 connected with a loop portion 63 which accommodates the pintle 64 carried by suitable ears depending from the plate 65, which plate is bolted or otherwise 50 rigidly secured to the extension 66 of the stationary wall 54. A pin 38' is carried by wall 39 and when the parts are in the position shown in Figure 2, a pin is spaced a short distance from plate 61 so that a genuine coin may strike shoulder 38 and then 55 move past the lower part of the plate 61 so as to rest on pin 40. When a piece of paper or light coin is stopped by the shoulder 37, it remains at this place until the plunger 27 60 is pushed. As the plunger moves, pin 38' will strike plate 62 and swing the parts to the position shown in Figure 4, whereby paper or spurious coins held by the shoulder 37, may fall down on to the floor 13. As 65 shown in Figure 4, there is an ample space

or chamber whereby any of these foreign articles may readily drop out of the way so that a clean path will be provided for the next true coin.

When the machine is in the position 70 shown in Figure 2 and a proper coin is inserted, it will drop down and strike the shoulder 37 and move the weighing device to one side and then will drop down until it strikes the pin 40 in front of the end of 75 pin 41. The plunger 27 is then pushed inwardly as far as possible. As the plunger moves inwardly, the coin is slid along the pin 40 and will strike against the pin 41. From Figure 2 it will be noted that the pin 80 40 extends beyond the wall 29 so that whenever the coin is released it will drop the coin in the coin box if the mechanism is being properly actuated. As the pin 41 moves, it will carry the ejector 46, which ejector will 85 strike the lowermost article 20 and force the same out of the magazine onto the chute 15. As soon as this has been done, the plunger 27 will be released and returned by the spring 52. As the plunger is returned, it 90 will carry with it the actuating frame including walls 29, and then in turn will move the magnet 36 back and this magnet will strike the pin 26 and move the pin 26 and associated parts back to their starting point 95 so that the parts are again in position for a second actuation.

What I claim is:

1. In a coin controlled vending machine, a manually actuated structure, an ejecting 100 structure, means for preventing the ejecting structure from moving back to its starting point when once started on the ejecting stroke, said means acting to prevent the return of the ejecting mechanism until the 105 full ejecting stroke has been made, a pivotally mounted member carried by the actuating means, and an actuated pin carried by the ejector formed with a notch for receiving said pivotally mounted member whereby the actuating means may move the ejector in one continuous movement or intermittently until it has completed its ejecting stroke, a magazine positioned so that the ejector on each stroke will force an article therefrom, 110 and guiding means for guiding the ejected article to a discharge point.

2. In a coin controlled vending machine, a magazine adapted to contain articles to be vended, a chute for directing said articles to a discharge point, an ejecting mechanism for ejecting articles from said magazine, said ejecting mechanism including a pin having a notch, a hand operated actuated mechanism for actuating said ejector, means for holding a coin in position to connect said actuating mechanism with the ejector, and a pivotally mounted member carried by said actuating mechanism positioned to engage said pin in said notch after the coin 120 125 130

has been disengaged from said coin holding means whereby the actuating structure may continue to move the ejector until it has completed its ejecting stroke.

5 3. In a coin controlled vending machine, a magazine adapted to contain articles to be vended, an ejecting mechanism for moving one article at a time from the magazine, and hand operated means for moving said ejector, said hand operated means being connected with the ejector by a coin, said hand operated means being provided with a pivotally mounted member having a bar, said ejector being provided with an actuating pin having a notch, a cam positioned to hold said bar out of engagement with said notch until the bar has moved a predetermined distance, and means for preventing said bar from moving back to its starting point until 10 it has completed its full stroke.

4. In a coin controlled vending machine, an ejecting mechanism, an actuating mechanism, said actuating mechanism including a pivotally mounted member having a bar, said ejecting mechanism including a pin having a notch for receiving said bar after the bar and pin have moved a certain distance, a cam for preventing said bar from moving into said notch until 15 said certain distance has been moved by the respective parts, a rack carried by said ejecting mechanism, and a spring held pawl co-acting with said rack, said pawl being capable of swinging against the action of 20 said spring in either of two directions, said pawl being so positioned in respect to said rack that it will prevent the return movement of the rack until it has moved a full stroke in one direction.

40 5. In a coin controlled vending machine, an ejector, an actuating frame for actuating the ejector, a stationary frame carrying said ejector and actuating frame, a projection extending from said stationary frame, a 45 looped guide carried by said actuating frame fitted over said projection for guiding said actuating frame, said stationary frame and said projection having aligned slots positioned in front of said looped member when 50 the looped member and actuating frame are in normally retracted position whereby said looped member must pass said slots as the actuating frame functions.

55 6. In a coin controlled vending machine, a magazine adapted to contain articles to be vended, a stationary frame, a sliding ejector mounted in said stationary frame and positioned to force the lowermost article from the magazine upon actuation, manually actuated means for causing said ejector to function, said means including an actuating frame formed with a coin guide, an actuating pin connected with said ejector and positioned in the path of movement of the

coin carried by said coin guide whereby 65 when a washer having a hole therein is deposited in said coin guide and the actuating frame operated, it will merely push the washer onto said pin, a ring surrounding said pin, and a spring actuating said ring for 70 forcing said washer off of said pin when said pin has been actuated by a correct coin, said correct coin being moved by said actuating frame and the coin in turn moving said pin until the coin presses the washer against 75 said ring whereby when the actuating frame is released the coin will be dropped and the spring pressed ring will force the washer off the pin.

7. In a coin controlled vending machine, 80 an ejector provided with coin-engaging means, with a notch and with a tooth member, a coin-carrying member formed with means for carrying a coin in line with said coin-engaging means, a plunger for actuating 85 said coin-carrying member for causing the coin to move said ejector to an ejecting position, a swinging member carried by said coin-carrying member adapted to engage said notch for moving the ejector to a fully 90 ejecting position in case the coin is dropped before the coin-carrying member has been moved a full stroke, and means engaging said tooth member for preventing a return of the ejector until it has been moved to a 95 fully ejecting position.

8. In a coin controlled apparatus, a magazine, an ejector for forcing articles from said magazine, a coin carrying member, said ejector including a throw-out member for 100 engaging and forcing an article from said magazine, a hand operated plunger rigidly secured to said coin carrying member for operating said coin carrying member, said coin carrying member being formed to hold 105 a coin between said plunger and said throw-out member so that as the plunger is operated said throw-out member will be caused to function, a spring for returning said throw-out member when released, a swinging 110 member mounted on said coin carrying member, notched means carried by said throw-out member positioned to be engaged by said swinging member in case the coin is released before a complete movement 115 of the throw-out member has been performed, a rack secured to said throw-out member, and a spring actuated pawl pivotally mounted on a stationary journal, said pawl being positioned to engage said rack 120 and prevent the return of said throw-out member until it has moved to a fully ejecting position.

Signed at New York in the county of New York, and State of New York, this 125 16th day of January, A. D. 1928.

DWIGHT T. CLARK.
